UNITED STATES PATENT OFFICE.

SAMUEL S. REESE, OF BROOKLYN, NEW YORK, ASSIGNOR TO ENDLOK PARTS CO., INC.,
OF NEW YORK, N. Y., A CORPORATION OF NEW YORK.

LOOSE-LEAF-BINDER LOCK.

Application filed May 12, 1925. Serial No. 29,704.

My invention relates to a new and improved loose leaf binder lock.

One of the objects of my invention is to provide a simple and automatic lock for connecting the two parts of a loose leaf binder.

Another object of my invention is to provide a lock of this character which shall automatically operate in all the relative positions of the two parts of the ordinary loose leaf binder.

Another object of my invention is to devise a lock of this character which shall operate by means of a frictional grip whose force will be increased by a pull the effect of which is to disengage the two bars commonly used in loose leaf binders.

Another object of my invention is to provide a lock of this character with a simple and efficient release.

Other objects of my invention will be set forth in the following description and drawings which illustrate a preferred embodiment thereof, it being understood that the above general statement of the objects of my invention is merely to generally define the same and not to limit it in any manner.

Fig. 1 is a top view.

Fig. 2 is a front elevation.

Fig. 3 is a sectional view on the line 3—3 of Fig. 2, the parts being shown in their locked position.

Fig. 4 is a view generally similar to Fig. 3 and shows the parts in their disengaged or released position.

Fig. 5 is a detail top view, a portion of the upper section being broken away and being shown in section.

Fig. 6 is a section on the line 6—6 of Fig. 1.

Fig. 7 is a perspective view of one of the lock members.

The fundamental parts of the loose leaf binder comprise a lower section 5 of any ordinary construction having end members 14 of well known construction to which a leaf 20 is hinged in the well known manner. All these parts, as well as the other parts of the device, may be made of any suitable metal. Sockets 11 are connected to the section 5, which may be designated as the lower section or member, and posts 6 and 7 of the usual construction are threaded into the said sockets 11, which are internally threaded in the well known manner. As shown more clearly in Fig. 4, the posts 6 and 7 may

be made of two parts connected by co-operating threading, in the well known manner.

The upper member 4 is of the usual construction and it is provided with end members 12 to which the metal leaf 1 is hinged in the ordinary and well known manner. This upper member 4 is provided with end webs 8 and with a central flange or web 9 as clearly shown in Fig. 4. The type of locking device utilized is clearly shown in Fig. 7. This consists of a cut-out lock member 16 adapted to rest upon the bottom of the upper member 4 and to be rigidly connected thereto by means of a rivet 17 whose position is shown in Fig. 5. Any number of such rivets may be employed.

The outer end of each lock member 16 is provided with notches and a locking member 15 made of resilient metal is provided with ears 19 which fit into these notches so that these ears 19 act as pivot members whereby each locking member 15 may be turned up and down. Each locking member 15 is provided with a hole through which a binding post may project as shown in Fig. 3, for example. Each locking member 15 is provided with an end notch, and a resilient metal tongue 18 connected to the lock member 16 by means of a rivet 22, presses upon the locking member 15, adjacent said end notch so that the said resilient lock tongue 18 acts to keep the member 15 in its lower position.

When the parts are assembled, the bottoms of the locking members 15 rest upon a release plate 10 which is kept in its lower position by means of a blade spring 3 and which can be moved up and down by means of a release member 2 whose shank passes through a hole in the resilient blade spring 3.

The operation of my device is as follows:—

The diameter of the hole H in each locking member 15, through which one of the binder posts passes, is substantially the same as the diameter of the said post so that when each said locking member 15 is perpendicular to the corresponding post, the said locking member or plate 15 can be slipped up and down the post with little or no friction.

However, if the locking plate 15 is tilted with respect to the post passing through it, as in the position shown in Fig. 3, then there is a sufficient tight fit between each post and the said hole H to firmly lock the

parts together if it is attempted to move a locking member 15 upwardly upon the post while it is in the said inclined position, as illustrated for example in Fig. 3.

5 Hence, when the upper part of the device is pushed downwardly upon the lower part of the device, this can be readily accomplished because the locking members 15 are forced into the horizontal position until the 10 upper part of the device has been pushed downwardly to the desired position. As soon as the downward pressure upon the upper part of the binder has been released, the locking tongues 18 force the locking 15 members 15 to the inclined or locking positions shown in Fig. 3, for example. If it is attempted to upwardly force the upper part of the loose leaf binder, this is prevented by the frictional engagement between the 20 locking tongues 18 and the respective posts passing through them and this frictional engagement increases in proportion to the unlocking force so that it is impossible to separate the two parts of the device.

25 However, the two parts of the binder can be readily disengaged by pulling upwardly upon the release member 2.

This causes the member 10 to be moved upwardly into the position shown in Fig. 4 29 so that the locking members 15 are moved into a substantially horizontal position and in this position they can be readily slid upon the binding posts so that the two parts of the device can be disengaged with little or no 35 effort.

It is obvious that the lock acts automatically and can be released very quickly and simply, and that the entire device can be quickly and cheaply manufactured and assembled.

40 I have described a preferred embodiment of my invention, but it is clear that numerous changes and omissions could be made without departing from its spirit.

45 I claim:—

1. In a loose leaf binder, the subcombination of a hollow and perforated binder section, a perforated lock member located within the said hollow binder section and having 50 a perforation aligned with a corresponding perforation in the said hollow section, and a locking plate turnably mounted upon the said lock member and having a perforation aligned with the before mentioned perforations.

55 2. A device according to claim 1 includ-

ing spring means mounted upon the said lock member and adapted to force the said locking plate to a position in which it is inclined to the common axis of the said perforations. 60

3. A hollow loose leaf binder section having a central portion and end portions, perforations extending through said end portions through which posts of a corresponding binder section are adapted to pass, lock members located within the said hollow section and connected to said end portions, the said lock members having perforations aligned with the first mentioned perforations, the said lock members having notches, locking plates provided with ears adapted to rest in the notches of the lock members so that the said locking plates are turnably connected to the said lock members, the said locking plates having perforations aligned with the before mentioned perforations, spring blades connected to the said lock members and contacting with the said locking plates and adapted to force them into a position in which they are inclined to the 70 common axis of the said perforations, a release plate having its ends extending under the free ends of the said locking plates, a manually operable member projecting through the central web and connected to 75 the said release plate, and a blade spring having a perforation through which said manually operable member is adapted to pass, the said blade spring being adapted to force the said release plate towards the bottom of the said hollow section. 80

4. A loose leaf locking device comprising a binder section having posts projecting therefrom, a second hollow binder section, lock members located within and secured to said hollow section, perforated locking plates removably and pivotally connected to said lock members at their lateral ends so as to have a free tilting movement, the said pivotal connections of said lateral ends being spaced from said hollow section, said posts being adapted to pass through the perforations in said plates, spring means adapted to urge said plates to a position inclined to said posts, and a release member located in said hollow section and adapted to move said locking plates from said inclined position. 100

105 In testimony whereof I affix my signature.

SAMUEL S. REESE.
